UNITED STATES PATENT OFFICE.

CHARLES F. YARDLEY, OF LARCHMONT, NEW YORK.

RAIL ANCHOR.

Application filed July 8, 1921. Serial No. 483,179.

To all whom it may concern:

Be it known that I, CHARLES F. YARDLEY, a citizen of the United States, residing at Larchmont, in the county of Westchester and State of New York, have invented certain new and useful Improvements in Rail Anchors, of which the following is a specification.

My invention relates to rail anchor devices, and has for its principal object the provision of a new and improved one-piece rail anchor device which may be easily applied to or removed from a rail, which will maintain its initial grip on the rail by spring pressure and which will increase its grip on the rail during the presence of a creeping pressure on the rail.

A more specific object of the invention is to provide certain improvements in the type of rail anchor described and claimed in my United States Letters Patent No. 1,201,415, dated October 17, 1916.

The invention consists in the provision of a new and improved anchor constructed as hereinafter described and claimed for carrying out the above stated objects, and such other objects as will appear from the following description.

The invention is illustrated in certain preferred embodiments in the accompanying drawings, wherein—

Fig. 1 is a plan view of a rail anchor constructed in accordance with my invention, the device being shown in its operative position in full lines and in its partially applied position in dot and dash lines.

Fig. 2 is a view in elevation of the anchor device shown in Fig. 1, the base flange of the rail being shown in cross-section;

Fig. 3 illustrates the blank from which the anchor device shown in Figs. 1 and 2 is formed;

Fig. 4 is a view in perspective of a modified form of device.

Fig. 5 is a view similar to Fig. 2, showing the modified form of anchor applied to a rail, the base flange of the rail being shown in cross section.

Fig. 6 is a view of one end of the blank from which the modified form of anchor, shown in Figs. 4 and 5, is formed.

Fig. 7 is a plan view of another modification; and

Fig. 8 is a sectional view taken on line 8—8 of Fig. 7.

Like characters of reference designate like parts in the several figures of the drawings.

Referring first to Figs. 1 to 3, inclusive, of the drawings, wherein I have shown one embodiment of my invention, made preferably from a flat metal blank of the configuration shown in Fig. 3: The anchor comprises a body portion 10, cut away as indicated at 11, to provide a recess for receiving the base portion 12 of a rail, a tie-abutting portion 13 adapted to bear, adjacent one edge of the rail base, against one of the vertical faces of a cross-tie 14, and a spring tongue portion 15 which projects over one edge of the rail base and bears against the upper surface thereof. The configuration of the recess 11 provides a jaw portion having a vertical edge 16 for engaging one of the base flanges of the rail and an angularly disposed lip 17 which extends towards the tie 14 and bears against the upper surface of said base flange. The vertical edge 18 of the other end of the recess 11 provides means for engaging the vertical surface of the other base flange of the rail. The distance between the vertical edges 16 and 18 of the recess 11 is, preferably, sufficient to permit the anchor to be applied to rails the base flanges of which, due to the wearing away of the rolls with which they are made, are slightly wider than the bases of perfectly formed rails. Any clearance between the edges of the rail base and the vertical edges 16 and 18 of the anchor will be taken up by shifting of the anchor to a diagonal position across the rail base. In order to minimize the distance between the vertical edges 16 and 18 of the recess 11 without making the application of the anchor more difficult, and without sacrificing the desired strength of the spring tongue 15 adjacent the edge 18, the edge 18 of the recess is preferably tapered outwardly, as shown at 19, from a point adjacent the upper edge of the rail base, so as to provide the necessary clearance to permit the edges 16, 18 to be engaged with the rail base. The tie-abutting portion is formed by bending the blank on lines 20, 21, to a position substantially as shown in Fig. 1. When properly bent, the post portion 22 of the tie abutment will be straight and converge with the edge of the rail in a direction toward the tie and the tie abutting foot 23 will project under the rail base and engage with the tie at a point near the edge of the rail base when the anchor is

in its operative position. The upper edge 24 of the tie-abutting foot is preferably in alignment with the upper edge of the body portion of the anchor, so that it will bear against the under surface of the rail base when the anchor is in its applied position. The tie-engaging surface of the foot 23 is formed, preferably, curved, so as to confine its engagement with the tie to a point adjacent the edge of the rail base, thereby providing a relatively wide bearing surface, and at the same time avoiding contact with the tie at points, for example, near the center of the rail, likely to resist the tendency of the anchor to assume a slight diagonal position across the rail base during the presence of a creeping pressure.

The spring tongue portion 15 is bent on line 25 of the blank to project toward the tie 14, and stands at an angle to the body portion, so that the distance between the vertical edge 16 of the jaw portion 26 and the end 27 of the tongue will normally be less than the width of the rail base to which the anchor is to be applied. The lower edge 28 of the tongue is formed with a taper which, when the tongue is bent to the position shown in Fig. 1 and the anchor applied to a perfectly formed rail, will correspond to the inclination of the upper surface of the rail base and bear against said surface, preferably, though not necessarily, from substantially the point 29 on the base to the end of the tongue.

It will be apparent, however, that the anchor can be applied to imperfectly formed rails, or rails having base flanges of different contours, and maintain a firm hold thereon by the tongue engaging the edge of the base at the point 29 only, or the anchor may be so formed, for example as shown in Figs. 4, 5 and 6, as to bear against the upper surface of the base at the end only of the tongue. The upper edge of the tongue is tapered downwardly toward its end, preferably on a straight line, to provide a cam surface 30 which facilitates the application of the device to the rail by forcing the tongue portion outwardly from the edge of the rail base when this end of the anchor is elevated until it clears the upper edge thereof, whereupon it will snap over the upper surface of the base.

In applying the anchor to a rail, the jaw portion 26 is hooked over one edge of a rail base with the tie-abutting foot 23 adjacent the tie 14. In this position the end of the spring tongue 15 extends under the rail base and the anchor assumes a general position substantially as shown in dot and dash lines in Fig. 1. The tongue end of the anchor may then be elevated by the use of a suitable implement (not shown) to bring the vertical shoulder or jaw 18 of the recess 11 in engagement with the edge of the rail

base. The inclined edge 30 of the tongue bears against the edge of the rail and functions as a cam to force the tongue outwardly until the tongue clears the upper edge of the rail base, whereupon it will spring over the edge of the rail base and exert a lateral spring pressure against the inclined surface thereof. In addition to the lateral spring pressure of the tongue on the rail base, a vertical pressure is produced by reason of a torsional strain to which the body of the anchor is subjected during the application of the device. When the anchor is applied to its initial position, it will normally be at an angle to the length of the rail, as shown in the dot and dash lines, from which position it may be driven to its operative position, so as to effect a firm shackle hold on opposite edges of the rail base. The spring action of the tongue and the torsional strain of the body portion operate to support the tie-abutting foot 23 in its proper position against the under surface of the rail base. The angularly disposed lip 17, in addition to assisting in supporting the tie abutting foot in its proper position, resists any tendency that the vertical chaffing movement of the tie-abutting foot against the tie may have to rock the anchor on a horizontal axis, and by such rocking movement impart an excessive torsional strain to the body portion of the anchor.

In Figs. 4 to 6 inclusive, I have shown a modified construction in which the overhanging lip 31 of the jaw portion 26^a, instead of being disposed at an angle, as shown in Figs. 1 and 2, is parallel with the body portion of the anchor. The lower edge 32 of the spring tongue 15^a is preferably so formed that, when the tongue is bent to its angular position, its end only will engage the upper surface of the rail base. In other respects, this construction may be the same as that shown in Figs. 1 to 3, inclusive.

In Figs. 7 and 8 I have shown another modification in which the recess 11^b, adjacent the jaw portion 26^b, is so formed that the vertical edge 16^b of the jaw does not contact with the vertical edge of the rail base. In this construction the lip 17^b of the jaw takes a wedging, frictional grip on the upper surface of the base flange of the rail. The spring tongue 33 of this form of anchor, instead of standing at an angle to the body portion, as shown in Fig. 1, curves inwardly toward the edge of the rail, as shown at 34. The lower edge 35 of the tongue may be formed with a taper corresponding to the inclination of the upper surface of the rail base, or it may be formed substantially as shown in Fig. 5, so as to bear at its outer end only against the upper surface of the rail base. This form of anchor, when in its preferred operative position, will normally stand at right angles to the length of the

rail, though it will be obvious that it could be driven to a diagonal position if desired.

The modified form of rail anchor shown in Figs. 4, 5 and 6 is not claimed specifically herein. The specific features of this modification have been divided out of this application and described and claimed in my copending application Serial No. 575,252 filed July 15, 1922.

10 I claim:

1. A one-piece rail anchor comprising a rail base embracing member formed at one end with a jaw for engaging one edge of a rail base, and with a tie-abutting portion, comprising a substantially straight post portion which converges with the edge of the rail base in a direction toward a tie and terminates in an angularly disposed flange adapted to bear against said tie, and formed 20 at the other end with a shoulder for engaging the other edge of a rail base and with a spring tongue adapted to bear against the upper surface of said base.

2. A one-piece rail anchor comprising a rail-base embracing member formed at one end with a jaw for engaging one edge of a rail base and with a tie-abutting portion comprising a post which converges with the edge of the rail base in a direction toward 30 the tie and terminates in an angularly disposed flange having a curved surface so as to confine its engagement with the tie to a point near the edge of the rail and formed at the other end with a shoulder for engaging the other edge of the rail base, and with a spring tongue adapted to bear against the upper surface of said base.

3. A one-piece rail anchor comprising a body portion formed at one end with a jaw 40 having an angularly disposed lip adapted to bear against the upper surface of the rail base and having a tie-abutting foot, the upper edge of which is adapted to engage the under surface of said rail base, and formed 45 at the other end with a shoulder for engaging the other edge of the rail base, and terminating in an angularly disposed spring tongue extending toward the tie against which the anchor abuts and bearing against 50 the upper surface of said base; said tongue being formed so that the distance between its end and said jaw is normally less than the width of the rail base to which it is to be applied and adapted to be forced outwardly 55 during the application of the anchor to a rail.

4. A one-piece rail anchor comprising a body portion formed at one end with a jaw 60 having a lip adapted to bear against the upper surface of the rail base and with a tie abutment formed to project under the rail and bear against the tie adjacent one edge of the rail base, and formed at the other end with a shoulder for engaging the other edge

of the rail base and with an angularly disposed spring tongue adapted to bear against the upper surface of said base; said spring tongue being formed so that the distance between its end and said jaw is normally less than the width of the rail base to which it is applied and adapted to be strained in its applied position so as to exert a slight 70 torsional strain to said body portion; said lip being angularly disposed with relation to said body portion so as to resist the tendency of rocking movements of the tie-abutting portion subjecting said body portion to excessive torsional strains.

5. A one-piece rail anchor device comprising a rail base embracing member 80 formed at one end with a jaw for engaging one edge of a rail, and with a tie abutment adapted to bear against a cross-tie, and formed at the other end with a shoulder for engaging the opposite edge of said rail and with a tongue adapted to snap over the upper surface of the rail base, so as to exert a slight torsional strain on said body portion; said jaw being formed with an angularly disposed lip adapted to resist downward 90 rocking movements of the tie-abutting portion.

6. A one-piece rail anchor comprising a body formed at one end with a jaw having a lip adapted to engage the upper surface of the rail base at one edge thereof and with a forwardly projecting portion providing a tie abutment and formed at the other end with a shoulder for engaging the opposite edge of the rail base, and with a spring tongue adapted to snap over the upper edge thereof; said lip being formed to project toward the tie to resist the tendency of said tie abutment to rock downwardly from the rail.

7. A one-piece rail anchor comprising a body portion formed with a jaw and a shoulder for engaging the opposite edges of a rail base and bent at one end to provide a tie abutment adapted to engage a tie adjacent one edge of the rail and formed at the other end with a spring tongue adapted to snap over and bear against the upper surface of the opposite edge of said base; the shoulder portion adjacent said spring tongue being formed with an outwardly tapered edge for the purpose described.

8. A rail anchor comprising a rail-base embracing member formed with a jaw and a shoulder for engaging opposite edges of the rail, a tie abutting portion, and with a spring tongue adapted to snap over the upper surface of said rail base; the lower edge of said spring tongue being formed with a taper which when the anchor is applied to a rail, corresponds to the inclination of the upper surface of the rail base, whereby said spring tongue will bear with

spring pressure against said upper surface from the edge of said base to the end of said tongue.

9. A rail anchor comprising a rail base 5 embracing member formed with a jaw and a shoulder for engaging opposite edges of said rail, and formed at one end with a tie abutment and at the other end with a spring tongue which extends diagonally across and

adapted to bear upon the upper surface of 10 said rail base; the upper edge of said tongue being formed with a straight, downwardly tapering surface providing a cam surface adapted to bear against the edge of said rail base and force the tongue outwardly during the application of the anchor to a rail.

CHARLES F. YARDLEY.
